UNITED STATES PATENT OFFICE.

MITCHELL H. WOODHULL AND CHARLES M. BLYDENBURGH, OF RIVERHEAD, NEW YORK; SAID BLYDENBURGH ASSIGNOR TO SAID WOODHULL.

CARRIAGE-POLE.

SPECIFICATION forming part of Letters Patent No. 366,442, dated July 12, 1887.

Application filed March 1, 1887. Serial No. 229,362. (No model.)

To all whom it may concern:

Be it known that we, MITCHELL H. WOODHULL and CHARLES M. BLYDENBURGH, of Riverhead, in the county of Suffolk and State of New York, have invented certain new and useful Improvements in Carriage-Poles; and we do hereby declare the following to be a full, clear, and exact description of the invention, such as will enable others skilled in the art to which it appertains to make and use the same.

The object of this invention is to improve the vehicle-pole described in patent of the United States, No. 287,412, bearing date October 30, 1883.

It consists in providing the tongue or straight portion of the pole A with arms sufficiently rigid and strong to withstand the great strain to which the arms in this class of poles are subjected, and, while avoiding the making of the arms large and heavy, retaining sufficient elasticity and range of variation at coupling-eyes to make a practicable adjustable pole.

In the accompanying drawings, Figure 1 represents top view of pole complete. Fig. 2 represents side view of pole. Fig. 3 represents pole in cross-section at E E.

To accomplish the desired result we use the straight or tongue portion A, (preferably of wood,) and divide or split it at its rear end a distance of about one (1) foot, and to each of such split or stub ends A we secure the larger end of hollow or U-shaped metal arms B by means of bolts or rivets C.

The arms B are made of metal formed hollow, but preferably U-shaped, and are provided at their free or rear ends with coupling-eyes D. By the arms being made of metal and of the shape of a U we get the maximum strength with the minimum weight and size.

As will be seen, the metal arms B are light, very rigid, and of small initial cost; but by attaching them at one end to the divided or stub ends of the tongue or pole A, sufficient elasticity is available in the divided ends A to give the arms B at their eye ends D a greater range of variation than is usually required in an adjustable pole.

Having described our invention, what we claim, and desire to secure by Letters Patent, is--

1. In an adjustable vehicle-pole, the straight or tongue portion split or divided at its rear end, said ends provided with hollow metal arms, substantially as set forth.

2. In an adjustable vehicle-pole, the combination, with the stub ends of tongue A, of U-shaped metal arms B, provided with coupling-eyes D, substantially as set forth.

MITCHELL H. WOODHULL,
CHARLES M. BLYDENBURGH.
